JAMES B. REPROGLE, OF DETROIT, MICHIGAN, ASSIGNOR TO JAMES B. REPROGLE LABORATORIES INC., OF BOSTON, MASSACHUSETTS, A CORPORATION OF MASSACHUSETTS

PUMPING MECHANISM

Application filed January 18, 1928. Serial No. 247,533.

This invention relates to pumping mechanism and particularly to a type thereof adapted for use as the compressor of mechanical refrigerating units, the principal object being 15 the provision of a pumping mechanism that is simple in design and construction, silent in operation, efficient in use, and economical to manufacture.

Another object is to provide a pumping 20 mechanism in which all wearing surfaces are formed of hardened steel.

Another object is to provide a pumping mechanism comprising a cylinder block which rotates about a line perpendicular to the axes 15 of the cylinders and in which the pistons rotate with the cylinders about a line eccentric to the axis of rotation of the cylinder block, whereby a relative reciprocation is caused between the cylinders and pistons, without actual reciprocation, which is utilized to effect 20 a pumping action.

Another object is to provide a pumping mechanism comprising a cylinder block rotatable about a line perpendicular to the axes of 25 the cylinders, and pistons rotatable with the block about a line eccentric to the axis of rotation thereof, a stationary head being provided for the cylinders and being provided with ports whereby the cylinders are ported 30 in a suitable manner upon rotation of the cylinder block.

Another object is to provide a compressor mechanism of the type described wherein the thrust on the pistons during the compression 35 stroke is taken up by a wearing surface independent of any sealing surface for the fluid being pumped.

Another object is to provide a compressor mechanism including a cylinder and piston 40 wherein the cylinder is ported on the suction stroke both at its head and at a point adjacent the head of the piston when the piston is at the end of its suction stroke.

Another object is to provide a pumping mechanism comprising a cylinder block having 45 a plurality of radially extending cylinders formed therein, the block being rotatable about a line perpendicular to the axes of the cylinders, and a piston for each cylinder being pivotally connected to an anchor member

rotatable about a line parallel with and eccentric to the axis of rotation of the cylinder block, the cylinder block being driven at the same speed as the anchor member by means of members fixed to the anchor member and 55 slidably engaging the cylinder block.

A further object is to provide a device of the type described comprising a sealed housing in which an axle member provided with an eccentric is fixed, a cylinder block being 60 rotatably received on the eccentric and being provided with pistons, the axle member being provided with anchor members rotatably mounted thereon on either side of the eccentric and connected together by tie members which extend through openings in the cylinder block and contact with the edges thereof, the pistons being connected by suitable links to the anchor members whereby upon rotation of the cylinders and pistons the distance 65 between the piston face and eccentric is caused to decrease and increase, and the eccentric being provided with suitable port openings which are opened and closed with respect to the various cylinders and in proper sequence upon rotation of the cylinder, the ports being connected by suitable axial passages in the axle member to suitable inlet and outlet ports. 70

The above being among the objects of the present invention the same consists in certain features of construction and combinations of parts to be hereinafter described with reference to the accompanying drawings, and then claimed, having the above and other objects in view. 75

In the accompanying drawings which illustrate a suitable embodiment of the present invention, and in which like numerals refer to like parts throughout the several different views,—

Fig. 1 is a vertical sectional view taken through the center of a compressor mechanism as on the line 1—1 of Fig. 3.

Fig. 2 is a sectional view taken on the line 2—2 of Fig. 1.

Fig. 3 is a view taken on the line 3—3 of Fig. 1, the lower half of the housing being removed to better illustrate the construction.

Fig. 4 is a side elevation of the eccentric axle member. 100

Fig. 5 is a view taken on line 5-5 of Fig. 4.

Fig. 6 is a sectional view taken on the line 6—6 of Fig. 5.

5 Fig. 7 is a sectional view taken on the line 7—7 of Fig. 5.

Fig. 8 is an enlarged vertical sectional view taken centrally through the combined packing and bearing for the drive shaft at the lower end of the lower housing half.

Fig. 9 is a view of the combined packing and bearing taken on the line 9—9 of Fig. 8.

Fig. 10 is a view taken on the line 10-10 of Fig. 1.

15 The present invention deals with a pumping mechanism which is particularly adapted for use as the compressor of refrigerating mechanisms of the mechanical compression type, and provides a construction that
20 is relatively noiseless in operation, vibrationless, compact and of extremely long life. As shown in the drawings it comprises a casing composed of an upper half 10 and lower half 11 of identical contour, each of which is
25 provided with a peripheral flange 12, the flanges being secured together by bolts 13 and nuts 14. Each casing half is provided with a central tubular neck portion 15. Received within the neck portion 15 of the upper half
30 10 is a sleeve member 16 secured against movement therein by the nut 17. Extending through the sleeve member 16 and fixed against movement therein by the nut 70 is an axle member 18 which extends into the interior of the housing where it is slightly enlarged as at 19 and 20 concentric with the portion 18, and is provided with an eccentric 21 between the portions 19 and 20. Rotatably received on the eccentric 21 is a cylinder
35 block 22 having formed therein four radially disposed cylinders 23 which are closed at their inner ends by the eccentric 21. The cylinder block 22 is held against axial movement relative to the eccentric 21 by the
40 flanged collar members 24 which are received on the portions 19 and 20 and secured in contact with the sides of the eccentric 21 by screws such as 25 as indicated in Fig. 4 with the flange portions thereof over-lapping the
45 joint between the eccentric 21 and the cylinder block 22. Rotatably received on the portions 19 and 20 above and below the collar members 24 are a pair of spider or anchor members 26 and 27 each of which is
50 provided with four equally spaced radially extending arms 28. The corresponding arms 28 of the spiders 26 and 27 are secured together in spaced relationship by means of tie rods 29 and nuts 30, the tie rods 29 extending through openings 31 in the cylinder block 22. The openings 31 are each of a diameter equal to double the eccentricity of the eccentric 21 with respect to the axis of
55 the shaft 18 plus the diameter of the tie rods 29 so that upon rotation each tie rod will be
60
65

constantly in contact with the edges of its corresponding opening 31, and when driving power is applied to the spider 27, as will be described, the spider 27 through the tie rods 20 in contact with the edge of the openings 31 will cause the cylinder block 22 to be rotated in exact constant angular relation therewith, and due to the relative motion of each of the tie rods 29 with respect to the openings 31 the driving force to the cylinder block will always be through that tie rod which is in contact with that portion of the corresponding opening 31 more advanced in the direction of rotation than the others. 70 75

In each of the cylinders 23 a piston 32 is received, and projecting vertically up through each of the pistons and perpendicular to their axes is a pin 33 which extends both above and below the cylinder block which is provided with slots 34 in the upper and lower surfaces of the wall of its cylinders to permit the necessary reciprocating movement of the pins 33 with the pistons 32. The pins 33 are anchored against movement along their axes by suitable locking means 35. A link or connecting rod 36 is pivotally secured by the bolts 37 and nuts 38 to the spiders 26 and 27 between each of the arms 28 and extend outwardly therefrom with their outer ends rotatably received on the ends of the pins 33. These links or rods 36 thereby tie the pistons 32 at a predetermined distance from the axis of the axle 18. It will thus be apparent that upon rotation of the cylinder block 22 and corresponding rotation of the assembly comprising the spider members 26 and 27, tie rods 29, pins 33 and pistons 32, and due to the fact that this assembly has an axis of rotation independent of and parallel to the axis of rotation of the cylinder block the pistons will have a relatively changing relation within the cylinders with respect to the eccentric 21 which terminates the cylinder opening and acts as and may be termed as a cylinder head; depending upon the particular phase of rotation that they happen to be passing through. When the device described is to be employed as a compressor, the pistons 32 are preferably so formed that their inner ends come into almost contacting relationship with respect to the surface of the eccentric 21 when in position closest to the eccentric, their faces being curved to conform to the curve of the surface of the eccentric 21 so as to cut down the clearance volume between them and the eccentric when in this position.

The cylinders 23 are ported in the following manner. An axial opening 39 is provided in the portion 20 of the axle 18 and leads from the lower end thereof to a point within the eccentric 21 where it meets the transverse opening 40 which emerges at the surface of the eccentric at such a position that its extreme edges are in simultaneous 125 130

engagement with the adjacent edges of the cylinder having its piston in most remote relation to the surface of the eccentric and the following cylinder respectively. Another 5 axial opening 41 is provided in the axle 18 and extends therethrough from its upper end to a point within the eccentric 21 spaced from the opening 39. An opening 42 connects the opening 41 with the exterior surface of the 10 eccentric 21 at a point thereon which lies at the diametrically opposite point on the eccentric 21 from the point where the opening 40 intersects it and in the same relationship with respect to the remaining two cylinders. 15 As indicated in Fig. 2 the size of the openings 40 and 42 on the surface of the eccentric 21 is slightly larger than the distance between the adjacent edges of adjacent cylinders 23 as measured on the surfaces of the 20 eccentric 21, so that the openings 40 and 42, both which serve as and are referred to as ports, are in communication with more than one cylinder at a particular time during rotation of the cylinder block 22 on the eccentric 25 21.

Referring to Fig. 2 and considering the cylinder block to be rotated in an anti-clockwise direction as indicated by the arrow shown in that figure, it will be apparent that the 30 distance between the faces of the pistons 32 and the eccentric 21 in moving from the left hand side of the figure to the right in rotating with the cylinder block will increase, and in moving from the right hand side of the 35 figure to the left hand side thereof will decrease. When the mechanism is in the position indicated in Fig. 2 the inner walls of the cylinder block substantially close the ports 40 and 41. Considering the left hand piston 40 in that figure, it will be apparent that it is at the end of the compression phase and its cylinder has just been closed to communication 45 with the outlet port 41. As this piston moves downwardly during operation through a distance of 90° it will assume the position indicated by the lower piston in that figure. During this phase of rotation it will be apparent that its cylinder has been closed to communication with either port 40 and 42 so 50 that a nearly complete vacuum has been set up in the cylinder. It will also be apparent that it is just being put into communication with the inlet port 40. During the next 90° of movement the piston will move to the position indicated by right hand piston in Fig. 55 2, and during this phase of movement its distance from the eccentric 21 will increase and at the same time the cylinder will be in communication with the inlet port 40 which will 60 allow the fluid being pumped to flow into the cylinder through the port 40 and opening 39, and will be cut off from communication with the inlet port 40 at the end of this phase of movement.

65 It is to be noted at this point that in

order to increase the volumetric efficiency of the device at high rotational speeds, I extend the slots 34 inwardly towards the center of the cylinder block a sufficient distance so that when the pistons 32 are at the most remote phase from the eccentric their ends uncover the inner ends of the corresponding slots 34 as indicated at 60, thereby providing an additional port for the entrance of the fluid being conducted to the cylinders. While 70 this feature is of marked advantage where the gas to be compressed is fed into the interior of a housing enclosing the mechanism as shown, it will, of course be necessary to eliminate the same where no such housing 80 is employed and a fluid different from the air in contact with the mechanism is being pumped. It will also be noted that the volumetric efficiency at higher speeds will also be aided due to the centrifugal action of 85 the device on the air entering the cylinders through the port 40.

During the next phase of movement the piston will move upwardly through an arc of 90° to the position indicated by the upper piston in Fig. 2, and during this phase of movement inasmuch as the cylinder will not be in communication with either port 40 or 42, the fluid which has been drawn into the cylinder through the inlet port 40 will 90 be partially compressed as the distance of its piston from the eccentric 21 decreases. During the next phase of movement the piston will move through an arc of 90° to the first mentioned position in which its distance from 95 the eccentric approaches zero, and during which phase of movement its cylinder is in communication with the outlet port 42, the fluid in the cylinder thus being driven out of the same and into the port 42 where it is 100 conducted to the opening 41 and discharged from the mechanism.

In practice I prefer to support the mechanism in an axially vertical position as indicated in Fig. 1, supported on a base such as 110 43 by means of standards 44 above an electric motor 45 or other suitable driving means. The motor 45 is provided with a shaft 46 to the upper end of which I secure the hub 47 of a fan 48 by means of a screw 49. The 115 blades of the fan 48 are each provided with an upwardly extending tongue 50 preferably struck out from the metal of the blades. The motor is connected to the mechanism in the following manner. A shaft 51 of relatively 120 small diameter is provided with tapered squared ends 52. To the upper squared end 52 is secured a member 53 which is closely received in the interior of the spider member 27 and is provided with radially extending pins 56 which are received in the slots 57 formed in the side walls of the spider member 27. The exterior surface of the member 53 is spherical in shape so as to be able to take up any 125 slight misalignment between the axes of the 130

shaft 51 and the spider 27. The lower squared end 52 is provided with a cross member 58 secured thereto by the nut 59 and has its outer ends bent downwardly to provide 5 attaching flanges. A coil spring 60' is held under tension between each end of the member 58 and each of the tongues 50 on the fan 48 thus resiliently connecting the shaft 51 to the fan 48 for equal rotation therewith. 10 This connection relieves any shock that otherwise might be transmitted between the motor 45 and the pump mechanism and serve to float the shaft 51 axially above the fan 48.

I provide a novel means for sealing the 15 lower end of the casing half 11 from leakage about the shaft 51. This means, as best shown in Figs. 1, 8 and 9, comprises a cup shaped member 61 which is closely received in the neck portion 15 and is provided with 20 an enlarged opening 62 in its otherwise closed end. The open end of the cup is provided with an outwardly extending radial flange 63 adapted to seat on the end surface of the lower neck portion 15. The shaft 51 projects 25 through the cup, the ends of which are closed by the split washers 64 and 65. Immediately surrounding the shaft 51 between the washers 64 and 65 is a mass of cellulose material 66 preferably impregnated with deflocculated 30 graphite, and compressed between this cellulose material and the sides of the cup is a mass of rubber 67 vulcanized in place. This provides a sealing means for the shaft 51 which is extremely long in life and substantially 35 frictionless. The assembly comprising the cup 61, washers 64 and 65 and the material within the cup is secured in place by the nut 68, a suitable gasket such as 69 being provided for preventing leakage between the out- 40 side of the cup and the neck portion 15. Should the bearing surfaces between the material 66 and the shaft 51 wear to such an extent that leakage occurs, it is only necessary to remove the nut 51 and unhook the 45 springs 60 whereupon the cup and the parts carried thereby with the shaft 51 may be removed and a new assembly of the same be inserted in its place.

In making the above described packing 50 for the shaft 51 I prefer to follow the following process. I tightly wind the shaft 51 for the proper distance with a suitable cellulose material such as long fibre cotton. I then impregnate the cellulose material with 55 deflocculated graphite as by dipping it in an aqueous mixture of the graphite. The washer 64 is then placed about the shaft 51 and inserted in the cup 61 in contact with the inwardly turned ends thereof. A predetermined 60 mass of rubber followed by the washer 65 is then forced into the cup between the sides thereof and the cellulose material 66 and the assembly is then subjected to a suitable vulcanizing heat which vulcanizes the 65 rubber to the cup and fills all possible inter-

stices in the cellulose material with rubber. If the cup is formed of brass the sulphur in the rubber will form a sulphite of the same which will firmly bind the rubber to the walls of the cup and prevent any possible leakage 70 at that point. Oil under pressure is then forced into the rubber with the result that the gradually growing action of the rubber because of the action of the oil upon the same tends to constantly compress the cellulose material about the shaft 51 and thereby take up any possible wear that may occur at this point.

The fluid to be pumped may be introduced 75 into the interior of the housing through the screw collar 53 which projects through the upper housing half 10 and is held in place by means of the nut 54. When employed as a refrigerant compressor the gasified refrigerant entering the housing through the collar 80 53 is directed against the moving mechanism, and the oil carried by the refrigerant is thereby discharged upon the moving parts and serves to lubricate the same. I prefer to 85 secure a small deflector such as 70 in the path 90 of the refrigerant flowing into the casing through the collar 53 so as to deflect some of the refrigerant and oil carried thereby against the upper end of the central bearing 95 for the upper spider member 26 so that the oil will be deposited upon the same so as to 100 lubricate it and will then be carried outwardly and lubricate other bearing surfaces. The gasified refrigerant and the oil thrown from the moving parts collects in the bottom 105 of the lower housing half 11 where it is drawn into the member 27 and then upwardly through the opening 39 and port 40 to the cylinders where it is compressed and discharged as previously described. By positioning the mechanism vertically as shown, 110 the oil in the casing is collected in the bottom of the same and is thereby prevented from coming in further contact with and being thrown about by the rotating parts, which would thus offer resistance to the rotation of such parts. In fact, inasmuch as the intake 115 passage 39 is positioned near the bottom of the casing, no great amount of oil may collect 120 in the casing, but only sufficient to afford ample lubrication for the bearing for the shaft 51 and serve to aid in sealing the same against leakage.

In supporting the device with its axis extended vertically as shown, it will be apparent 125 that a thrust is set up due to the weight of the assembly comprising the spiders 26 and 27, tie rods 29 and other connected parts. This thrust is taken up at the point of contact between the upper collar 24 and the upper spider 26, and the contacting surfaces at this point are beveled as indicated to provide more perfect and longer wearing surfaces.

In the preferred embodiment of this pump mechanism I form all of those parts whose 130

surfaces may be subject to wear of steel, and harden and grind such surfaces so that all wearing surfaces are hardened steel against hardened steel. This insures substantially no wearing of the parts in operation which would otherwise tend to permit leakage of the gas being compressed during the compression phase of operation and thereby render the operation of the device less efficient, and provides a construction in which substantially no service is required. The loss of efficiency usually present due to friction of piston rings and similar devices is minimized in this device by the use of hardened ground and lapped steel or other hard surfaces, as close fits can be produced without prohibitive commercial expense sufficiently close to reduce leakage to permissible amounts. Such fits are impractical with softer materials and render piston rings imperative.

It will be further apparent that by the construction shown the possible wear due to the load exerted on the pistons during the compression stroke will in no way tend to produce a leakage of gas from the cylinders due to such wear. This is due to the fact that the act of compression exerts no force on the cylinders radially of the eccentric, the actual force being directly between the eccentric and the face of the pistons, the reaction being transmitted through the pistons to the pins 33 and through the links 36 to the spiders 26 and 27 and where it is taken up between the same at the point where they bear on the portions 19 and 20 of the eccentric axle. Any wear from this cause thereby takes place between the spiders 26 and 27 and the portions 19 and 20 respectively, which wear has no effect whatever on the seal between the cylinder block 22 and the eccentric 21. All of the parts are, of course, amply lubricated when the device is being employed in a refrigerating system by the lubricating oil carried by the refrigerant, because such oil will be directed into exterior contact with these parts and deflected to the center bearing upon entering the housing and will be carried through the interior of the mechanism while the refrigerant is being drawn into and compressed within the same.

Although a device of this construction may be made with only one cylinder, it is preferable that at least two and preferably more cylinders are provided. Where two or more cylinders are provided the device may be perfectly balanced dynamically inasmuch as the cylinder block has only rotary motion and the assembly comprising the spiders 26 and 27, rods 29, pistons 32, pins 33, and links 36 have an only rotary motion without reciprocation. With the exception of the very slight swinging movement of the links 36 on the bolts 37 no actual reciprocation, except the relative reciprocation of the pistons in the

cylinders, takes place, which results in the elimination of reciprocatory forces and this permits the mechanism to be rotated at high speeds without setting up any secondary or higher vibrational forces during operation such as are bound to be present in the usual piston type of pump construction. Further, when a plurality of pistons are employed in a device of this type, the resistance which is built up by the compression of the fluid to the driving of the mechanism, and which is commonly referred to as the stall torque, is cut down and merged by them whereby a more even torque is produced which permits the mechanism to be driven by motor having less torque than would otherwise be necessary. In view of the fact that all the motion is substantially rotary which thereby permits the mechanism to be driven in a relatively higher speed than in the conventional constructions, a relatively greater amount of fluid may be pumped with the device shown than in a mechanism of conventional construction, a relatively greater amount of fluid may be pumped with the device shown than in a mechanism of conventional construction and of the same size. This permits a relative reduction in the size of the device which results in less weight and permits it to be manufactured more economically. Further, because the device may be driven at high speeds it may be driven directly from a comparatively small electric motor such as shown which eliminates the expense and noisy operation of speed changing devices.

Although I have shown but one embodiment of the present invention it will be readily apparent that it is capable of various and numerous modifications which may be necessary or desirable to adapt it for use for one purpose or another, such as, for instance, the increasing of the size of the ports in the eccentric to adapt the construction for use in pumping liquids, which modifications will be readily apparent to those skilled in the art, and formal changes may be made in the specific embodiment of the invention described without departing from the spirit or substance of the broad invention, the scope of which is commensurate with the appended claims.

What I claim is:

1. In combination, a fixed stationary member, a cylinder rotatable about said member and closed at one end thereby, a piston in said cylinder rotatable about a line eccentric to the axis of rotation of said cylinder, a port in said member communicating with said cylinder upon rotation thereof, and a port in said cylinder controlled by the reciprocation of said piston therein.

2. In combination, an imperforate casing, a centrally disposed stationary member fixed at one end in said casing, an eccentric formed

- on said member, a cylinder block rotatably mounted on said eccentric and provided with cylinders closed at their inner ends by said eccentric, pistons in said cylinders, means connecting said pistons to said member in a constant radial relation therewith, an inlet port in said eccentric, an outlet port in said eccentric, a passage connecting said inlet port with a point within and adjacent the bottom of said casing, a passage connecting said outlet port with a point exterior to said casing, and an inlet passage for said casing entering said casing at a point above said cylinder block.
15. 3. In a device of the type described, a stationary member provided with an eccentric, a cylinder block rotatably mounted on said eccentric, radially disposed cylinders formed in said block closed at their ends by said eccentric, pistons in said cylinders, said block being provided with a plurality of axially parallel openings, a spider member rotatably mounted on said member on either side of the said eccentric, rods extending between and secured to said spider members passing through said openings and slidably engaging the edges thereof, a pin secured in each of said pistons perpendicular to the axes thereof, connecting rods pivotally connecting said pins and said spiders, and inlet and outlet ports in said eccentric.
4. In a fluid pump, in combination, an imperforate casing, a vertically disposed support in said casing, a cylinder block rotatable on said support, a member rotatable on said support above said cylinder block and eccentrically with respect to said cylinder block, a cylinder in said cylinder block, a piston in said cylinder, means connecting said member and said piston whereby said piston is caused to rotate about the same center as said member, said support being provided with an inlet port connecting said cylinder with the interior of said casing adjacent the bottom thereof, said casing being provided with an inlet opening adjacent the top thereof, and a deflector for deflecting fluid entering said opening against said member adjacent its point of bearing on said support.
45. 5. In a compressor structure through which gas and oil travel in cycle, a sealed casing having an inlet through which gas and oil are drawn by suction, a compressor means in the casing having an exposed bearing, a deflector directing at least some of the incoming gas and oil upon the bearing, and means through which gas compressed by the compressor passes from the casing.
55. 6. In combination, a sealed casing, a fixed stationary member in the casing, a cylinder rotatable about said member and closed by one end thereof, a piston in the cylinder, a pair of duct means establishing communication of the cylinder with the exterior of the casing through the stationary member,

and another duct means controlling communication between the cylinder and the casing for supplying an additional quantity of fluid thereto, said duct means being controlled by the piston.

7. In a compressor, a fixed cylinder head provided with an eccentric portion, a cylinder block rotatably mounted on the eccentric portion of the head, radially disposed cylinders formed in the block and closed at their inner ends by the eccentric portion of the head, pistons in the head, said block being provided with a plurality of axially extending parallel circular openings, a spider member rotatably mounted on the cylinder head on either side of the eccentric portion, rods extending between and secured to said spiders and passing through the openings and engaging the edges thereof, the openings having a diameter equal to double the eccentricity of the eccentric portion of the head plus the diameter of the rod passing therethrough, driving means connected with one of the spiders, and link connections between the pistons and the spiders maintaining the pistons concentric relative to the axis of the cylinder head.

8. In a compressor, a fixed cylinder head provided with an eccentric portion, a cylinder block rotatably mounted on the eccentric portion of the head, said block having openings therein parallel with the axis, pistons in the cylinder block, spiders on either side of the eccentric portion of the cylinder head, pins connecting the spiders and extending through the openings in the cylinder block, means for rotating the spiders, the engagement of the pins with the edges of the cylinder block openings causing rotation of the block around the eccentric portion of the cylinder head, and means maintaining the pistons in a concentric relation with the cylinder head axis.

9. In a compressor, a fixed cylinder head provided with an eccentric portion, a cylinder block rotatably mounted on the eccentric portion of the head, said block having slotted cylinders open to the cylinder head, means for rotating the cylinder block including connected spiders, pistons in the cylinders, pins extending through the pistons and cylinder slots, and links pivotally associated intermediate the spiders and pin ends maintaining the pistons concentric with the cylinder head.

10. In a compressor, a fixed cylinder head having an eccentric portion, an apertured cylinder block rotatably mounted on the eccentric portion of the head, said cylinder block having slotted cylinders closed at one end by the head, a pair of spiders arranged one on either side of the eccentric and concentric with the head, pins extending through the apertures in the block and securing the spiders rigidly together, said pins engaging the edges of the block forming the apertures to rotate the block, means for rotating one of

the spiders, pistons in the cylinders, pins traversing the pistons and projecting through the slots in the cylinders, and links pivotally connected between the ends of the pins and the spiders maintaining the pistons concentric with the cylinder head axis.
